UNITED STATES PATENT OFFICE

RALPH H. MANSON, OF PITTSBURGH, PENNSYLVANIA, ASSIGNOR TO HUBBARD AND COMPANY, A CORPORATION OF PENNSYLVANIA

INSULATOR SUPPORT

Application filed January 26, 1929. Serial No. 335,201.

This invention relates to supports and more particularly to insulated supports or clamps for electric cables such, for example, as the current conveying cables or lines associated with an electric light pole or the like.

An object of this invention is to provide a device of the type described of improved construction and arrangement.

A further object is to provide a device of this type constructed and arranged so as to prevent separation of the parts when the same are unclamped.

These and other objects which will be apparent to those skilled in this particular art are attained by means of this invention, one embodiment of which is illustrated in the accompanying drawings in which Figure 1 is a view in elevation of a portion of a light-supporting pole equipped with a cable support constructed in accordance with one embodiment of this invention. Fig. 2 is a similar view on an enlarged scale of the insulated cable support or clamp. Fig. 3 is a view of the end of the device showing the parts in open position. Fig. 4 is a transverse sectional view on the line 4—4 of Fig. 2 and Fig. 5 is a similar view showing a different means for trapping the insulator parts in the associated bracket parts.

Insulated cable supports or brackets are commonly employed, for example, for supporting or guiding an electric cable or the like 10, which is carried down an associated pole 11 from the usual cross arm 12 to a light supporting arm 13 or the like. These brackets are usually constructed of separable parts which support a two part insulator through which the cable extends and the various parts of the bracket and insulator have heretofore been so arranged that, when unclamped they became entirely separated from each other and were extremely clumsy and awkward to handle, especially high up on a pole.

The present invention includes a two part bracket 14 having a pole engaging part 15 adapted to be mounted upon or secured to an associated support by any desired means such, for example, as the screw threaded end 16 thereof. The projecting end of the bracket part 15 is formed as a strap member 17

adapted to partially embrace an associated insulator part 18 which co-operates with a corresponding insulator part 19 positioned within a supporting strap 20. The strap 20 has an ear 21 pivoted to a corresponding ear 22 of the supporting strap 17 by any suitable means such, for example, as the screw pivot 23 which will permit the parts to be moved to open position but at the same time will prevent actual separation of the strap member 20 from the supporting strap member 17. The screw pivot 23 is provided with a flared end 24 so that it cannot be removed entirely from the supporting ear 22. The opposite end of the strap member 20 has an ear 25 provided with an open slot 26 adapted to be moved into and out of co-operative engagement with a clamping screw 27 supported in an ear 28 formed on the end of the strap member 17 opposite from the ear 22.

In the present invention, the co-operating surfaces of the insulator parts and the supporting straps or bracket parts are so formed that each insulator part is trapped in the insulator receiving recess formed in the associated bracket part so as to positively prevent any separation of the insulator parts from the bracket parts when the clamp is opened for the purpose of inserting or removing a cable or the like, such position being illustrated in Fig. 3. In the construction illustrated in Fig. 4, this is accomplished by crimping the portions of the collars 17 and 20 adjacent the ears thereof so as to narrow that portion 29 of the recess in which the associated insulator part is received.

This is, of course, accomplished after the insulator part is placed therein, and serves effectively to prevent dropping of the insulator from the bracket when the bracket is unclamped and opened by an operator who has climbed the pole for that purpose.

It will be apparent that many different means can be provided for accomplishing this purpose. For example, Fig. 5 illustrates an additional way which includes the provision of insulator engaging tongues 30 on the strap members which are pressed inwardly so as to fit within tongue receiving apertures 31 molded in the insulator blocks.

It will be apparent that the present construction provides an arrangement which will enable an operator to ascend the pole and open the clamp so as to insert or remove a cable or wire therefrom without any danger of the bracket parts or the insulator parts from becoming separated and dropping to the ground. It will also be apparent that the strap members 17 and 20 can be hinged or pivoted together by any suitable means other than the pivot screw 23 which will permit the strap member 20 to be moved to open or closed position with relation to the supporting part or bracket.

What I claim as new and desire to secure by Letters Patent is:—

1. The combination in a cable support of a bracket member adapted to be mounted upon a supporting pole or the like, and having a U-shaped insulator receiving recess in said bracket, a U-shaped insulator part mounted in said recess, tongues on said bracket members adapted to be bent inwardly into engagement with said insulator part for preventing separation thereof from said recess, a U-shaped insulator supporting strap hinged to said bracket adjacent said recess, a second U-shaped insulator part positioned in said strap, tongues on said strap member adapted to be bent inwardly into engagement with said second insulator part for preventing separation thereof from said strap, and means for clamping said strap to said bracket so as to hold said insulator parts in co-operative position.

2. The combination in a cable support of a bracket having a strap member provided with outwardly extending arms forming a recess therein, an insulator section having the outer edges thereof tapered inwardly adapted to be received within said recess, a second strap member having outwardly extending arms thereon, an insulator member similar to the above-mentioned insulator adapted to be received within the second strap member and means extending through the outwardly extending arms of said strap members for securing the same together, the outwardly extending arms of said strap members being crimped at points adjacent the inwardly tapering outer edges of said insulator members for securely holding said members in place in said recesses.

3. The combination in a cable support of a bracket having a curved strap member, outwardly projecting ears on said strap member, a U-shaped insulator member adapted to be received within said strap member, a second curved strap member, outwardly projecting ears on said second curved strap member adapted to cooperate with the ears on said first strap member, a U-shaped insulator member adapted to be received within said second curved member and means extending

through apertures in said ears for securing said strap members together, the outer ends of said curved strap members being bent inwardly into locking engagement with said insulator members for securely holding said members in place therein.

4. The combination in a cable support, of a bracket having a U-shaped strap member, a U-shaped insulator member having inwardly tapering outer edges adapted to be received within said strap member, a second U-shaped strap member, a second U-shaped insulator having inwardly tapering outer edges adapted to be received within said second strap member, the ends of said strap members being crimped into engagement with the tapered edges of said insulator parts for preventing separation thereof from said strap members and means for securing said strap members together.

5. The combination in a cable support of a bracket member adapted to be mounted on a supporting pole or the like, a U-shaped insulator receiving recess in said bracket, outwardly extending ears on the arms of said bracket, a U-shaped insulator member having shoulders on the outer edges thereof adapted to be received within said recess and held therein by the engagement of the arms of said U-shaped bracket member with the shoulders on said insulator member, a U-shaped strap member adapted to co-operate with said bracket adjacent said recess, outwardly extending ears on said strap member, a second U-shaped insulator member similar to the first-mentioned insulator member adapted to be received in said second strap member and to be held therein by the engagement of the arms on said strap member with the shoulders on said insulator member and means extending through apertures in the ears of said strap and bracket members for holding said insulator members in co-operative position.

In testimony whereof, I have hereunto subscribed my name this 24th day of January, 1929.

RALPH H. MANSON.
